UNITED STATES PATENT OFFICE.

FREEBORN F. RAYMOND, 2d, OF NEWTON, AND CHARLES H. FOGG, OF HYDE PARK, MASSACHUSETTS, ASSIGNORS TO JAMES W. BROOKS, OF PETERSHAM, AND JOHN BROOKS, OF CAMBRIDGE, MASSACHUSETTS, TRUSTEES.

DEVICE FOR FEEDING NAILS.

SPECIFICATION forming part of Letters Patent No. 571,931, dated November 24, 1896.

Application filed October 3, 1895. Serial No. 564,491. (No model.)

To all whom it may concern:

Be it known that we, FREEBORN F. RAYMOND, 2d, of Newton, in the county of Middlesex, and CHARLES H. FOGG, of Hyde Park, 5 in the county of Norfolk, in the State of Massachusetts, citizens of the United States, have invented a new and useful Improvement in Devices for Feeding Nails, &c., of which the following is a full, clear, and exact description, reference being had to the accompanying drawings, forming a part of this specification, in explaining its nature.

The invention relates to means for holding a large number of nails or other fastenings 15 in order for delivery and for feeding them automatically in such order to a distributer by which they are received, transferred, and arranged in any desired order for delivery to a nail-carrier.

20 The invention is represented in the drawings as applied to a heel compressing or attaching machine. We have discovered that it is desirable to use for the purpose of holding and feeding the nails or fastenings a circular disk or plate in which there is made or 25 arranged a large number of radial or diverging lines of nail receiving and holding holes, the lines being placed as closely together as is practical, and the holes in each line also 30 being placed closely together, the lines of holes preferably beginning at some distance from the center of the plate or disk. The nail-holding holes of the disk or plate extend through it and are preferably of the same size 35 and are covered, excepting at the point of delivery, by a cover-plate which is beneath the nail-holding plate. The nail-holding plate is adapted to be moved vertically in relation to the cover-plate in order that any nails or parts 40 of nails which may have lodged between the two may be easily removed therefrom. The nail-holding plate and the cover-plate are movable vertically together to provide access 45 to the nail-distributer, and they are also moved vertically and laterally away from the nail-distributer to provide further access to the distributer by uncovering it and also means by which it may be removed and another of a different order of distribution substituted.

The invention further relates to means for rotating the nail-holding plate and for operating the cover-plate to uncover one or more lines of holes therein at the desired time, and to various other features of construction and 55 operation, all of which will hereinafter be more fully described.

In the drawings, Figure 1 is a view in side elevation of our improved nail holding and feeding device. Fig. 2 is a view in plan thereof, a portion of the nail-holding and covering plates being broken out to show parts below the same. Fig. 3 is a view in end elevation of the device, the nail-holder and cover-plate being shown as removed from the distributer. 60 Fig. 4 is a view in rear elevation showing the position of parts when the nail-holding plate and cover are in operative relation with the nail-distributer, and Fig. 5 is a view in vertical central section through the device and the 65 nail-distributer. Fig. 6 is a view in plan representing the nail holding and feeding plate, a portable skimmer thereon, and devices for centering or registering the skimmer upon the plate. Fig. 7 is a view in horizontal section taken through the nail holding and feeding plate and the skimmer when in position thereon, its cover-plate not being removed. Fig. 8 is a detail view of a portion of the skimmer, its cover, and a cover-locking device. 70 Fig. 9 is a view in section representing the skimmer upon the nail holding and feeding plate and the cover of the skimmer removed to permit its nails to be fed to the holes of the nail holding and feeding plate. Fig. 10 75 is a view in perspective of the skimmer removed. Fig. 11 is a detail view of the skimmer, representing one method of securing the cover-plate thereto.

A is the nail holding and feeding plate. It 80 is in the form of a disk and it has the lines a of nail holding and feeding holes arranged closely together radially and of any desired number. The holes extend through the plate. The plate preferably is of iron. It has a central opening a' within the flange a^2 , the flange resting upon the shoulder a^3 of the hub a^4 , which is keyed to the upper end of the shaft B. Rotation is given the plate A to advance 85 one or more lines of holes with the nails 90 95 100

therein in regular order to the holes *c* of the nail-distributer *C* by means of the worm-wheel *B'*, fast to the lower end of the shaft *B*, and the worm *B²* upon the horizontal shaft *b*, 5 the worm being in constant engagement with the worm-wheel, and the shaft *b* being turned by means of the gear-wheel *B³*, carrying a driving-pawl *b'*, which engages the ratchet-wheel *B⁴* on said shaft *b*. The gear-wheel *B³* 10 is free upon the end of the shaft *b* and is rotated forward and back by the sector-gear *B⁵*, pivoted at *b²*, (see Figs. 1 and 3,) which has a reciprocating oscillating movement imparted to it by means of the nail-carrier plate 15 *D*, having a nail-carrier *d*, by which the nails are transferred from the distributer to the nail-driving devices, and which plate is moved forward and back at stated intervals by a cam, (not shown,) a lever *d'*, the upper part 20 of which is represented in Fig. 5, and a connecting-link *d³*.

From the nail-carrier plate *D* there extends backward the arm *d³*, the rear end of which is connected with the sector by means of a 25 link *d⁴*, which may have lost motion provided it by means of the slot *d⁵* and stud *d⁶*, which passes through it and which connects it with the end of the arm *d³*. A spring *d⁷* connects the link with the stud and tends to draw it 30 toward the stud. The end *d⁸* of the link is connected with a stud *d⁹* on the sector *B⁵* by means of an open bearing *d¹⁰*, and a spring-latch *d¹¹* secures the end of the link to the 35 stud and also permits it to be readily detached therefrom.

The movement of the nail-carrier plate *D* back and forth imparts a reciprocating or oscillating movement to the sector *B⁵*, which in turn rotates the pinion *B³* backward and forward, causing the driving-pawl *b'* to turn the shaft *b* as it is moved in one direction by the pinion and to ride backward over the teeth of the ratchet-wheel *B⁴* as it is revolved in the opposite direction, the ratchet-wheel being held from following this return movement by means of the stop-pawl *b³*. (See Fig. 2.) 40 As the pinion *B³* is small, the driving-pawl *b'* is secured to a larger disk *b⁴*, attached to the pinion, (see Fig. 2,) the pawl being pivoted thereto, (see Fig. 1,) and the disk carrying a spring *b⁵*, which bears on the back of the pawl. The rotary movement thus imparted to the shaft *b* rotates the worm in one direction and causes it to slowly turn the 45 nail holding and feeding plate *A*, and at the end of the turning movement it locks it in place as well, and the friction of the worm and worm-wheel on each other assists in holding the shaft *b* stationary during the backward movement of the driving-pawl *b'*.

The shafts *B* and *b* and the bracket to which the sector *B⁵* is pivoted are provided with vertical movements and also with horizontal movements, the said parts being supported or 50 carried by the arm *E*, in which the shaft *B* has a bearing, and which arm *E* is supported by a stud or post *e* at one side of the center of

the device, the stud being fixed to a portion of the frame of the nail-driving mechanism or to any other stationary support and the 70 arm extending laterally therefrom and being attached thereto to swing horizontally thereon and be also movable vertically thereon. The arm is locked with the parts in operative position by means of the short extension *e'* 75 and the clamping-screw *e²*, (see Fig. 2,) which has a head *e³* and passes through a hole or recess in the said end *e'* and a hole in a stationary bracket *e⁴* and has an outer threaded end which receives the clamping-nut *e⁵*, the clamp- 80 ing-nut clamping the arm *e'* against the bracket *e⁴*. When the nail-holder and other parts are to be moved from operative position, this clamping-screw is released and the arm *E* and the parts which it carries are moved 85 upward by means of the spiral lifting-incline *E'* on a sleeve *e⁶* on the lower part of said post or stud *e*. It is adapted to be turned by the lever *e⁷*, (see Fig. 2,) and incline *E'* turns against the spiral incline *E*, and this causes 90 the arm *E* to be raised the required distance. The incline *E'* ends in a straight bearing-section *e⁸*, which upon the turning of the arm rides upon the straight top of the sleeve *e⁶* beyond the incline *E'*. 95

F is the cover-plate. It preferably is a cast-metal plate of a size to cover the holes of the nail-holding plate, excepting those adjacent to the point of delivery, where it is pieced out or has added to it a thinner sheet-metal or steel section or plate *f*, which is adapted to continue the covering of the holes to a line just beyond the holes in the distributer and to uncover the holes of the nail-holder to permit the nails to pass from one or 100 more lines of holes therefrom into the holes of the distributer. The cover-plate has a slight movement or rotation given it, the plate returning to its hole-covering position before the nail-holding plate has been moved 105 sufficiently to advance a filled line of holes. The plate is cut away or opened beyond the edge of the cover enough to permit any nails remaining undelivered in the holes of the nail-holding plate to drop from it after they 110 have been moved from register with the holes of the distributer. The cover-plate is moved to uncover the holes at the proper intervals by means of a rock-shaft *f'*, having an arm *f²* at its upper end, which engages a pin *f³* near 115 the outer edge of the cover-plate at its back, and an arm *f⁴* at its lower end, which is adapted to be moved at practically the end of the backward movement of the nail-carrier plate *D* by a bracket *f⁵*, attached to the reciprocating arm *d³*, the bracket preferably carrying a 120 striking-section which is adjustable thereon and which is represented as made in the form of a screw-stud *f⁶*, freely movable therein, having a head at one end and a nut *f⁷* at the 125 other, by which the length of the projecting end *f⁸* of the stud may be regulated in relation to the bracket and the time and the extent of the movement of the rock-shaft thus varied. 130

It will be understood that the nail-holding plate preferably is fed upon the forward movement of the nail-carrying plate D and remains stationary during the backward movement thereof, and as the nail-carrying plate reaches the end of its backward movement the cover-plate is moved sufficiently to uncover one or more lines of holes of the nail-holding plate over the distributor. Upon the forward movement of the nail-holder plate the cover-plate is released and the spring f⁹, attached thereto and to a fixed point on the arm E, immediately returns it to its covering position. The plate F has a hub f¹⁰, which surrounds the part of the arm E furnishing the bearing for the shaft B. (See Fig. 5.)

The nail-holder plate A has in its flange a² holes g, through which extend pins G, fast to the shoulder or flange a³. These pins prevent the nail-holding plate from turning on the hub a⁴ and also provide means by which the plate A may be lifted from the cover-plate when desired. The pins further act to register the large skimmers or filling-plates H, (shown in Figs. 6 and 7,) which are made in the form of sectors in which are a large number of lines of holes corresponding with the lines of the corresponding section of the nail-holding plate A. This perforated sector-plate is adapted to be filled by hand or otherwise and to transfer the nails from the place where received to a position over the plate A. It has in its inner edge holes h, which register with two of the pins G, and it also has handles h' and a cover-plate h², which is movable outwardly from the under side of the plate H when its holes are in register with the holes of the plate A. (See Fig. 7.) To cause the nails to be started and dislodged from the sides of their holding-holes when they have arrived at a point over the distributor, we have attached to the machine a plate I, (see Fig. 2,) having an upwardly-curved outer edge i, (see Fig. 4,) which is carried at the end of an arm i', pivoted at i² to a stationary support.

It will be understood that the holes of the nail-holding plate A are not deeper than the nails, the ends of the nails generally extending above the top of the plate, and they ride under the plate I, so that generally it bears upon the tops of the nails, and the vibration of the nail-driving machine causes the plate to have sufficient tremor or movement to act to loosen and help eject the nails. The plate also acts as a cover-plate in preventing nails from being jarred from the nail holding and feeding plate at this point.

The distributor C has the upper perforated plate c', in which there may be one or two lines of holes, generally two lines, which lines diverge and register with the two lines of holes of the nail holding and feeding plate. The distributor also has a lower plate c², which has holes c³ of any desired arrangement, and tubes having nail-passages connect the holes of one plate with the holes of the other. The

two plates are attached to each other by the posts c⁴, one at each end, and the distributor is held in place by means of a button c⁵, which buttons upon the lower plate, and the stationary abutment c⁶, against which the side c⁷ of the upper plate comes in contact.

The operation of the machine is as follows: The holes of the nail holding and feeding plate 75 are filled with nails or fasteners either by hand or by means of the removable skimmer or loader. The distributor C is put in place and the nail-driving machine actuated, and this causes the nail holding and feeding plate 80 A to be turned, the lines of nails to be brought by successive impulses over the distributor and discharged therein.

We would not be understood as limiting the invention to its employment in feeding nails 85 and fastenings, as it is obvious that it can be used for feeding any other article or thing which it is desirable to hold and feed automatically in large numbers and distribute in any desired arrangement for any other manipulation or action.

The loading-skimmer (shown in Figs. 6, 7, 9, and 10) has ledges or flanges at each end for the retention of the cover formed by flat pieces N, attached to each end of the plate 95 and having inwardly-extending flanges n slightly below the under surface thereof. These flanges diverge on account of the shape of the edges of the plate, and the cover-plate h² slides into them from the front edge of the 100 plate. It is secured to the skimmer by the ends which slide upon the flanges n. It is of thin metal and has at its outer edge the handles n², by which it is inserted and withdrawn. A button n³, secured to the edge of the skimmer, drops in front of the edge of the cover when it is in place and secures it there. The skimmer also has handles h', by which it is transferred. They are preferably swinging or bail handles and are placed closely to each end 110 of the skimmer, so that when in a horizontal position they will extend beyond each end and leave the entire upper part of the skimmer unobstructed. They are preferably formed as represented in Figs. 6 and 7; that is, one 115 arm, n⁵, of the handle is attached by a screw pivoted to the front edge of the skimmer, and the other arm, n⁶, has at its end a horizontal extension n⁷, which enters a housing or box n⁸, secured to the top of the skimmer within 120 the perforated section. The skimmer also has the centering-holes before referred to, which coöperate with the centering-pins G, as already explained.

Having thus fully described our invention, 125 we claim and desire to secure by Letters Patent of the United States—

1. In a machine of the character specified, a nail-holding plate A having a large number of lines a of nail-holding holes arranged there- 130 in and guides upon which said plate is vertically movable without being detached from the machine.

2. The nail-holder plate A, having an in-

- ner flange a^2 to rest upon the shoulder a^3 of the rotary central plate a^4 .
3. The rotary plate a^4 , having a shoulder a^3 , a nail-holding plate A having a flange a^2 , and 5 means for fastening the flange and shoulder together.
4. The rotary plate a^4 and the nail-holder plate A, vertically movable in relation thereto.
5. The rotary plate a^4 , having pins G, and 10 the nail-holding plate A having holes in its inner edge through which said pins extend.
6. A nail-holding plate having a large number of nail-holding holes arranged in rows 15 therein and a portable nail-holder having a similar arrangement of nail-holding holes, and means for centering the portable holder above the nail-holding plate with its lines of nail-holding holes in line with the nail-holding holes of the nail-holding plate.
- 20 7. The combination of a nail-holding plate A having intermittent periods of rotation and rest, and provided with a flat upper surface and skimmer-registering devices movable therewith with a portable skimmer to rest upon said plate and be registered by said registering devices, the holes of which are of the same order and arrangement as the holes of the section of the nail-holding plate over which it is placed, and a removable cover 25 therefor adapted to be withdrawn after the plate has been registered.
8. The combination of the nail holding and feeding plate, the registering-pins G, with the nail-feeding skimmer having holes upon its 30 inner edge to register with the pins G, the nail-holding skimmer being in the form of a sector-plate and having a cover-plate movable outwardly therefrom.
9. A nail-holder skimmer in the form of a 35 perforated sector-plate having sections of registering devices, handles and a removable cover-plate.
10. In a machine of the character specified, a nail-holding plate in the form of a segment- 40 plate provided with a large number of radiating holes arranged therein, having a bottom or under plate removable outwardly therefrom, whereby the plate is adapted to hold in a relatively small compass a large 45 number of nails, and whereby it is also adapted to feed nails to a section of a circular nail holding and feeding plate having nail holding and receiving holes of similar arrangement, as and for the purposes set forth.
- 50 11. A movable nail holding and feeding plate and an upwardly-movable plate I arranged over the nail holding and feeding plate to operate as specified.
12. A movable nail holding and feeding 55 plate and the plate I having the curved edge i arranged over the nail holding and feeding plate to operate as specified.
13. A movable nail holding and feeding plate with a plate I pivoted to an independent 60 support and arranged to bear upon the tops of the nails carried by said plate.
14. A movable nail holding and feeding 65 plate provided with nail-receiving holes from which the upper ends of the nails project, in combination with a nail-discharging plate I 70 arranged over the nail holding and feeding plate at the point where the said plate discharges its nails and which is adapted to assist in said discharge, as and for the purposes specified. 75
15. In a machine of the character specified, a nail holding and feeding plate having holes for the reception of nails with a cover-plate arranged over said nail holding and feeding plate and adapted to prevent upward movement of the nails from the said nail holding and feeding plate as said plate is being fed or as the machine is being operated. 80
16. The movable nail holder and feeder having the plate I arranged over a portion thereof as specified and attached to the machine to be movable by a swinging movement out of operative relation therewith. 85
17. A movable nail holding and feeding plate and an under cover-plate beneath the 90 same, one being movable vertically in relation to the other.
18. A rotary nail holding and feeding plate having intermittent forward rotation imparted to it and a cover-plate beneath the 95 nail holding and feeding plate having a narrow aperture extending inward from its edge and provided with a slight interrupted oscillating movement. 100
19. In a machine of the character specified, a circular nail holding and feeding plate in combination with a worm-wheel attached thereto and an intermittently-operated worm arranged to engage the worm-wheel and which acts to move the nail holding and feeding 105 plate and also to lock the said nail holding and feeding plate at the end of its feeding movement and to hold it locked in said position. 110
20. The rotary nail holding and feeding 115 plate, a nail-transferring plate or carrier and actuating devices for rotating the said nail holding and feeding plate, which devices are connected with the nail transferring or carrier plate, and operated thereby. 115
21. The combination of a nail-transferring plate or carrier, an oscillating sector-gear connected with said plate, or its actuating device, to be oscillated thereby, a worm-wheel connected with a nail holding and feeding 120 plate, a worm to engage said worm-wheel, and intermittently-operated devices between the worm-wheel and sector-gear comprising a pinion to mesh with the sector-gear, a feed-pawl carried thereby and a ratchet-wheel 125 with which said feed-pawl engages connected with the said worm-wheel, as and for the purposes described. 125
22. The combination of the nail holding and feeding plate, the worm-wheel B' connected therewith, the worm B², its shaft b, the ratchet-wheel B⁴ secured thereto and the oscillating feed-pawl b' to engage the teeth of the ratchet-wheel. 130

23. The combination of the nail holding and feeding plate, the worm-wheel B' connected therewith; the worm B² which engages the worm-wheel B', the shaft b, the ratchet-wheel b⁴ carried thereby, the stop-pawl b³ and the driving-pawl b' attached to a pinion B³, free upon the said shaft b, and means for rotating the pinion forward and back, as and for the purposes described.

10 24. The combination of the nail holding and feeding plate, its actuating worm-wheel, the worm B² and its actuating devices detachably connected with the movable nail carrier or transferrer.

15 25. The combination of the worm-operating sector B⁵, the reciprocating arm d³, and the intermediate link-latch d⁴.

20 26. The combination of the worm-operating sector B⁵, the reciprocating arm d³, having a stud d⁶, the link connecting the stud with the sector having the slot d⁵, and the spring d⁷.

25 27. The combination of the worm-operating sector B⁵, with the connecting-link d⁴, having the sector-stud bearing d¹⁰, and spring-latch d¹¹.

30 28. In a nail holding and feeding mechanism, a nail holding and feeding plate of the character specified, having a large number of nail-holding holes and an under cover-plate therefor, both of which plates are vertically movable together, as and for the purposes specified.

35 29. In a nail holding and feeding mechanism, a nail holding and feeding plate having a large number of nail-holding holes and an under cover-plate therefor, both of which plates are adapted to be moved laterally together, as and for the purposes described.

40 30. In a nail holding and feeding mechanism, a nail holding and feeding plate having a large number of nail-holding holes, an under cover-plate therefor, the said nail holding and feeding plate and said cover-plate both being vertically and laterally movable together, as and for the purposes described.

45 31. In a nail holding and feeding mechanism, a nail holding and feeding plate having a large number of nail-holding holes, an under cover-plate therefor, the said nail-holding plate and cover-plate being adapted to be moved first vertically and then laterally, as and for the purposes described.

50 32. In a nail holding and feeding mechanism, a nail holding and feeding plate having a large number of nail-holding holes, an under cover-plate therefor, the said plates being adapted to be separated vertically and also to be moved vertically in their separated relation, as and for the purposes described.

55 33. In a nail holding and feeding mechanism, a nail holding and feeding plate having a large number of nail-receiving holes, an under nail cover-plate, the two plates being separable vertically in relation to each other, and both of said nail-plates being laterally

movable in their separated relation, as and for the purposes described.

34. In a nail holding and feeding mechanism of the character specified, the combination of a vertically-movable nail holding and feeding plate adapted to hold a large number of nails and feed them in successive order to a nail-distributer, with said distributer, as and for the purposes described.

70 35. In a nail holding and feeding mechanism, the combination of the distributer C, with nail holding and feeding plate and a plate-cover both vertically movable with relation to the nail-distributer.

75 36. In a nail holding and feeding mechanism, the combination of the distributer, with nail holding and feeding plate and its cover-plate, both movable vertically and laterally in relation to the distributer.

80 37. In a nail holding and feeding mechanism, the combination of the distributer, the nail holding and feeding plate, the movable cover-plate and the stay or registering plate c⁶, against which the upper part of the distributor is held in contact.

85 38. In a nail holding and feeding mechanism, the combination of the nail holding and feeding plate, its cover-plate, an arm supporting the same and means for moving the arm vertically.

90 39. In a nail holding and feeding mechanism, the combination of the nail holding and feeding plate, its cover-plate and an arm for supporting the same pivoted to a stationary stud or post at one side of the center of said nail-holding plate.

100 40. In a nail holding and feeding mechanism, the combination of a nail-holding plate, its cover-plate and supporting mechanism, and means for moving it vertically, comprising the two inclines E', E², bearing opposed relation to each other, and one of which is movable in relation to the other.

110 41. In a nail holding and feeding mechanism, the combination of the nail holding and feeding plate, its cover and means for supporting them both, and devices for lifting them and holding them in their lifted position, comprising the inclines E', E², ending in flat surfaces and one of which is movable in relation to the other, their flat surfaces coming together at the end of the lifting movement and acting to support the parts in their lifted position.

115 42. In a nail holding and feeding mechanism, the combination of the post or support e, an arm pivoted thereto carrying at its outer end a nail holding and feeding plate and cover-plate, the said arm having a horizontal swinging movement upon said pivot and means carried by said pivot for moving said arm vertically thereon and for holding it in its vertical position during the swinging movement of said arm.

120 43. In a nail holding and feeding mechanism, the combination of the lifting and swing-

- ing arm E, the nail holding and feeding plate and cover-plate carried thereby, their operating mechanism also carried by said arm to be movable vertically and horizontally there-
5 with, a detachable connection between said operative devices and the movable part of the machine upon which the feeding apparatus is used, as and for the purposes de-
scribed.
- 10 44. The combination of the nail holding and feeding plate, its cover-plate, the movable arm E for supporting the same and means for locking said arm with the nail holding and feeding plate and cover-plate in operative po-
15 sition.
45. In a nail holding and feeding mechanism, the combination of the nail holding and feeding plate, the cover-plate, and a supporting-arm, pivoted as described, having a short
20 end e' and a stationary bracket or arm against which said short end is brought in contact, as and for the purposes described.
46. In a nail holding and feeding mechanism, the combination of the nail holding and feeding plate, the cover-plate and a supporting-arm E, pivoted as described, and having a short end e' and a stationary bracket, and means for fastening the arm to the said bracket.
25
47. In a nail holding and feeding mechanism, the combination of the nail holding and feeding plate and its cover-plate, both laterally movable, and means for locking them in their operative position.
30
48. In a nail holding and feeding mechanism, the combination of the nail holding and feeding plate, the cover-plate, a rock-shaft connected therewith to move it in one direction, and a movable part of the machine to
35 which the nail-feeding apparatus is attached which communicates movement to said rock-shaft.
49. In a nail holding and feeding mechanism, the combination of the nail holding and feeding plate, the cover-plate and a rock-shaft connected therewith, the rock-shaft having an arm with which a tappet is adapted to be brought into contact.
45
50. In a nail holding and feeding mechanism, the combination of the nail holding and feeding plate, its cover-plate, a rock-shaft connected therewith, its tappet-arm and an adjustable tappet.
50
51. In a nail holding and feeding mechanism, the combination of the nail holding and feeding plate, its cover-plate and an arm operated by a tappet for actuating the same and an adjustable tappet.
55
52. In a nail holding and feeding mechanism, the combination of the nail holding and feeding plate, the cover-plate, the cover-plate-operating devices, and a reciprocating tappet for actuating the same.
60
53. In a nail holding and feeding mechanism, the combination of the nail holding and feeding plate, its cover-plate, and operating mechanism and means for actuating the cover-
65

plate-operating mechanism, comprising a re-
ciprocating tappet, the said tappet consisting
of a threaded stud carried by a reciprocating
part, and a nut for adjusting the relation of
the end of the stud to said reciprocating part.
70

54. In a nail holding and feeding mechanism, the combination of the nail holding and feeding plate, its cover-plate, a lever or rock-
shaft for moving it in one direction, and a
spring for moving it in the reverse direction.
75

55. In a nail holding and feeding mechanism, the combination of the nail holding and feeding plate, its cover-plate, the nail-carrier
80 and connecting devices for operating the cover-plate at the end of the backward movement of the nail-carrier.

56. In a nail holding and feeding mechanism, the combination of the nail holding and feeding plate, the cover-plate, the nail-carrier, a tappet carried thereby, a tappet-arm connected with the cover-plate, and a spring for returning the cover-plate and reversing the position of the tappet-arm, as and for the
85 purposes described.

57. In a nail holding and feeding mechanism, the combination of the nail holding and feeding plate, the cover-plate, the nail-carrier plate, and means connecting it with the nail holding and feeding plate to rotate it during the forward movement of the carrier-
90 plate, and other means connecting the carrier-plate with the cover-plate to operate it at the end of the backward movement of the carrier, substantially as described.
95

58. In a nail holding and feeding mechanism, the combination of a nail holding and feeding plate, the cover-plate, the distributor having uncovered passages therein, the nail-carrier and devices for moving the nail holding and feeding plate upon the forward movement of the nail-carrier and for actuating the cover-plate to uncover the holes in said nail holding and feeding plate upon the backward movement of the nail-carrier.
100

59. In a machine of the character specified, a portable skimmer or loader having a nail-holding section in the form of a segment-plate in which the nail holding and receiving
115 holes are arranged in a large number of radiating lines, which holes correspond to a similar arrangement of holes in the nail holding and feeding plate, as and for the purposes specified.
120

60. In a machine of the character specified, the portable skimmer or loader having flanges at each end and a cover-plate sustained by said flanges.

61. In a machine of the character specified, a portable loader or skimmer in the shape of a segment-plate having a large number of radiating lines of holes therein and provided with an under cover-plate detachably secured to the said skimmer by its edges only, and adapted to be moved outwardly from the front edge thereof to uncover its holes.
125
130

62. In a machine of the character specified, the combination of a portable loader or skim-

mer having a large number of nail-holding holes therein, a removable under cover-plate attached by its edges only to the said skimmer and adapted to be moved outwardly from its front edge in uncovering the holes therein and handles attached to the front edge of said cover-plate shaped to hook upon the outer surface of the skimmer when the cover-plate is in its closed position, whereby they serve also to sustain the front edge of the cover-plate when the skimmer is loaded with nails.

63. In a machine of the character specified, the portable skimmer or loader, a cover-plate attached to the under surface of the skimmer or loader and a lock for fastening it to the skimmer or loader, substantially as described.

64. In a machine of the character specified, a portable skimmer or loader having sections of a registering device in combination with other sections of a registering device mounted upon or carried by the nail holding and feeding devices.

65. In a machine of the character specified, the portable skimmer or loader having an inner flange provided with registering holes.

66. In a machine of the character specified, in combination with the nail holding and feeding plate, the portable skimmer or loader, having a cover removable from its front edge, means for centering the skimmer or loader with its attached cover upon the nail holding and feeding plate in a manner to permit the withdrawal of the cover from the front edge thereof, as and for the purposes described.

67. In a nail holding and loading machine of the character specified, a nail holding and loading plate circular in form, having radial lines of holes extending entirely around it and divided by skimmer or loader registering or centering devices into sections, each of which is provided with centering or registering devices for receiving and locating a portable nail-holder or skimmer, substantially as described.

68. In a nail feeding and loading apparatus of the character specified, a rotary nail holding and feeding plate divided into sections of equal length by centering or registering devices of the same character and arrangement, each of which is adapted to receive any one of a number of portable skimmers or loaders and center it or register it, whereby the same or a uniform portable skimmer or loader may be employed with each section of the nail holding and feeding plate, as and for the purposes described.

69. In a nail holding and feeding device of the character specified, a slowly-moving nail holding and feeding plate having centering or registering devices thereon which move with it, and a portable loader or skimmer adapted to be centered or registered by said centering or registering devices upon said nail holding and feeding plate and while it is in motion, whereby the nail holder and feeding plate may be loaded with nails without interfering with or stopping the operation of the machine, substantially as described.

70. The combination in a machine of the character specified of a nail holding and feeding plate having a large number of nail-receiving holes adapted to be moved to deliver said nails in successive order, with a portable skimmer or loader having a large number of nail-receiving holes of the arrangement of the holes of the nail holding and feeding plate, adapted to be mounted upon said last-named plate, and an independent under cover-plate for said portable skimmer or loader, the said portable skimmer or loader being adapted to be moved with the nail holding and feeding plate.
